ATTORNEY

UNITED STATES PATENT OFFICE.

WILLIAM W. HAYDEN, OF NEWARK, NEW JERSEY.

DESIGN FOR A MATCH-BOX.

SPECIFICATION forming part of Design No. 21,636, dated June 21, 1892.

Application filed May 13, 1892. Serial No. 432,929. Term of patent 3½ years.

To all whom it may concern:

Be it known that I, WILLIAM W. HAYDEN, a citizen of the United States, and a resident of Newark, in the county of Essex and State 5 of New Jersey, have invented and produced a certain new and original Design for Match-Boxes, of which the following is a specification.

The accompanying drawing, forming a part 10 of this specification, illustrates my newly-designed match-box or receptacle for small articles.

My new design relates to the form and ornamentation of the body and top or cover of 15 the box; and the leading feature consists of a corrugated formation rising from a fancy ornament at the bottom or closed end of the box.

A represents the body of the box, B the top or cover, and C C' and D D' the corrugated 20 formation. The corrugations are slightly spiral or diagonally arranged, and those marked C reach from the ornament around one edge and to the top line F of the body, while those marked C' cover one corner and edge of the

body and are oppositely arranged and appear 25 to run under the corrugations C. The corrugations D D' of the cover join the corrugations C C' of the body to produce a continuous effect, and at the top of the cover appears the heart-shaped center-piece D². The top of 30 the cover is therefore ribbed and curved, the corrugations gradually diminishing in size from the center to each edge. The ornament at the bottom of the box comprises the central fig-leaf-like member a, the two edge members b b, also in the form of fig-leaves, curved 35 around the edges of the box, and the triangle c at the center of the member a. The members b b join the central member a, forming spirals d d at the corners of the box, as clearly 40 shown.

I claim—

The design for a match-box, as herein shown and described.

WILLIAM W. HAYDEN.
